UNITED STATES PATENT OFFICE.

ROY L. WILLIAMS, OF VAN ALSTYNE, TEXAS, ASSIGNOR OF FORTY-EIGHT PER CENT
TO OSCAR T. HUNT, OF GUNTER, GRAYSON COUNTY, TEXAS.

MAGAZINE HAMMER.

Application filed June 8, 1926. Serial No. 114,426.

This invention relates to automatic magazine hammers and shingling hatchets and it has particular reference to a novel mechanism so constructed as to select and place 5 a tack or nail in a position to be driven, in addition to certain expediences for successively opening and closing the nail delivery passageway at each operation and employing for such mechanism a minimum 10 number of parts.

The invention further aims among its objects to provide a novel trigger assembly making possible the above action, as well as a feeding means disposed in such a manner as to progressively hold the nails in 15 a position which will not interfere with the operation of the hammer or hatchet as the case may be.

With the foregoing objects and advantages in view the invention consists further in the novel construction and arrangement of parts by which the foregoing objects are attained, and which will be manifested in the course of the following detail 20 description and illustrated in the accompanying drawings wherein:

Figure 1 represents a side elevational view of a hatchet and nail feeding means constructed according to the present invention. 25

Figure 2 is a fragmentary underside view of the magazine handle, showing the nail feeding means and delivery.

Figure 3 is a fragmentary side elevational 35 view of the invention partly in section, showing the position of the nails alined for delivery.

Figure 4 is a detail view, with portions broken away, of the delivering lever assembly. 40

Figure 5 is a view of the reverse side of the delivery lever assembly.

Nail driving tools of such design as to afford an automatic feeding means are known 45 to have been heretofore advanced with an effort to avoid having to manually place the nail in position for setting with the hammer, and to further expedite the work of such a tool in various ways, therefore 50 the present invention does not claim as new the broad idea of automatically placing the nail for setting with the hammer, but does claim as new and novel, the mechanism described herein for singly releasing and placing the nail and closing the delivery pas-

sage against release of the nails, and automatically opening such passageway for the reception of another charge, all of which is accomplished by a single trigger disposed upon the handle of the implement. 60

With the above in view the invention consists primarily of a hollow handle or magazine 1, for the reception of nails or tacks 2, which, as shown in Figure 1, is closed at its end by a plug 3. An opening or channel 4, the depending sides of which are integral with the handle 1 is cut in the underside of said handle, and is of such width as to permit passage of the nail body but not the head. 65

Detachably affixed to the forward end of the channel 4 is a delivery chute 5, slightly inclined toward the ball of the head 6, and, as shown in Figure 3, is likewise equipped to receive only the heads of the nails 2 and 70 permit the same to slide freely downward, after having been released through the enlarged aperture 7 in the handle by gravity. Referring more particularly to the transfer 75 of the nails from the handle to the chute 5; the nails after having been placed in the handle 1, finally assume a uniform, perpendicular position therein as in Figure 3, and upon swinging the hammer in driving, the column of nails move forward and are held 80 from displacement when entering into the delivery chute by the depending tongue 8, see Figure 3. The nail heads pass beneath this tongue and pass through the opening 85 7 onto the shoulder provided within the chute 5 and downward to where they are stopped by a shoulder 9 at the end of the chute, as in Figures 2 and 3. 90

A bracket 10, also preferably integral with the handle 1, depends at the end of the latter 95 adjacent the head 6, and as shown in Figure 5 especially is secured by any suitable means to the lower end of the chute to support the latter and positively hold the same in correct position with respect to the head 6. To this bracket 10 is pivoted a pair of co-acting levers 11 and 12, termed herein as a delivery lever assembly. These levers, by reason of the lugs 13 thereon as in Figure 4 especially, have limited independent movement on the pivot 14, with respect one to another, but are adapted to move the greatest distance simultaneously as will be presently disclosed. It will be noted in Figure 1 that the outer lever 11 is provided with a nail receptacle 15, 110

which is adapted to register with the opening at the shoulder 9 on the delivery chute 5 when receiving a nail and through the action of the spring 16, which is secured to the lever and to a rigid part of the chute 5, a closing action of the receptacle 15 is obtained by reason of the lower portion of the lever 12 sliding thereover as particularly apparent in Figure 4.

10 The trigger 17, shown in Figures 1 and 2, is provided with a sheath 18 through which the same passes to where it is pivotally secured to the top of the lever 12. After receiving a nail from the chute 5, forward 15 movement of the levers 11 and 12 to carry the nail into the position shown in dotted lines in Figure 1 is effected by pulling upon the trigger 17. This action very obviously pivots the two levers 11 and 12, the springs 16 and 19 acting independently upon the levers causes the under lever 12 to which the trigger 17 is affixed, to move forward a limited distance in advance of the outer lever 11, such action causing the lower portion of the 25 former lever 12 to move to enclose the nail received in the receptacle 15, such an action likewise closing the discharge end of the chute 5 to shut off the remaining nails by the smooth inner surface of the lever 12 as the 30 two levers move forward, see Figure 5.

Now, when the nail is in a position below the shoulder 20 integral with the head 6 for striking, the latter action is carried out to set the nail while the trigger 17 is held with 25 the finger. When the nail is set, the trigger is released and the springs 16 and 19 return the levers 11 and 12 back to their normal positions, and since the receptacle 15 is provided with a lip 21, see Figure 2, to prevent 40 its passage by the shoulder 9 of the receptacle 5, the lever 11 is stopped at this point, while the tension of the spring 19 upon the companion lever 12 causes the latter to move a limited distance beyond the opening in the 45 chute, sufficient to permit another nail to fall within the receptacle 15, and the setting action is repeated.

From the foregoing, it will be readily seen that there is no possibility of clogging of 50 the nails at the point of transfer from the handle 1 to the chute 5, nor from the latter to the receptacle 15 of the lever 11, and in the latter action, the delivery of only a single nail is insured by the co-active relationship of the two levers 11 and 12, aided by the springs 16 and 19, when the trigger 17 is actuated.

While the invention has been described as including all the elements referred to in the 60 appended claims, it should be understood that certain minor changes and modifications may be resorted to as to form and assembly of parts as fall within the meaning and scope of the said claims.

65 I claim:

1. In a magazine hammer, a nail feeding means including a detachable inclined delivery chute having its receiving end open to the said magazine; a bracket integral with said magazine and supporting the delivery 70 end of said chute; a pair of co-acting levers pivoted on said bracket, one of said levers having a receptacle disposed to register with the delivery end of said chute to receive a single nail; tension means to hold said receptacle normally over said chute delivery; means on said magazine to cause the levers to pivot forwardly, and means to effect closing of said receptacle by the other lever to hold said nail against displacement. 80

2. In a magazine hammer, a nail feeding means including a detachable inclined delivery chute having its receiving end open to a channel in said magazine; a support for the discharge end of said chute; a pair of co-acting levers having limited movement with respect one to another and having a common pivotal point on said support; a nail receptacle on one of said levers arranged to register with the delivery end of said chute; means to hold said receptacle normally over said delivery end; means connected to the other of said levers to cause pivotal movement of said levers to carry said nail from the chute, and means to cause the other lever to simultaneously cover said receptacle to prevent displacement of the nail contained therein. 90

3. In a magazine hammer, an automatic nail feeding arrangement including an oblique delivery chute having its receiving end communicating with said magazine; a support for the delivery end of said chute; levers having a common pivotal point on said support and arranged to cover the delivery end of said chute; means on one of said levers disposed to successively register with said delivery end of said chute to receive nails therefrom; means on said magazine to pivot said levers to convey the nails from said delivery chute to a point of disposal, and means to automatically cause one of the levers to cover said nail receiving means upon passage from said delivery chute. 100

4. In a magazine tool, a nail delivery including an inclined chute; a pair of co-acting levers having a common pivotal point arranged to cover the delivery end of said chute; a receptacle on the outer of said levers to register with said chute delivery end; tension means to hold the outer lever in the latter position; and means on said magazine arranged to be moved against the action of said tension means to pivot said levers and to move the inner of said levers over the receptacle in said outer lever to close the same. 110

5. In an automatic nail feeding tool, a magazine handle and head; a nail delivery 120

130

- chute inclined toward the ball of said head and having its receiving end communicating with said magazine; a pair of levers mounted on a common pivot adjacent the delivery end of said chute; one of said levers having a nail receptacle normally registering with said delivery end; tensioning means for each of said levers; and means to effect common pivotal movement of said levers against the action of said tension means to move said receptacle away from said chute delivery end, said action to simultaneously cover said receptacle by the other of said levers.
6. In an automatic nail feeding tool, a hollow handle and a head therefor, a chute inclined toward the ball of said head having communication with said hollow handle, a lever pivoted adjacent the delivery end of said chute having a receptacle arranged to successively register therewith; a lever rearward of said first lever having means thereon to successively cover the receptacle in said first lever; tension means for each of said levers; and means on said handle arranged to act against said tension means to actuate said levers.

In testimony whereof I affix my signature.

ROY L. WILLIAMS.
